Primary Examiner — Michael A Maharajh

(57) **CLAIM**

We claim the ornamental design for a game ball, as shown and described.

DESCRIPTION

FIG. 1 is a perspective of the game ball.
 FIG. 2 is a front side view of the claimed design.
 FIG. 3 is a rear view of the claimed design.
 FIG. 4 is a left side view of the claimed design.
 FIG. 5 is a right side view of the claimed design.
 FIG. 6 is a top view of the claimed design; and,
 FIG. 7 is a bottom view of the claimed design.

1 Claim, 7 Drawing Sheets(56)
